(57) **CLAIM**

I claim the ornamental design for an earplug support frame, as shown and described.

DESCRIPTION

FIG. 1 is a perspective view of first embodiment of an earplug support frame, embodying our new design, a mirror image earplug support frame is evident from the earplug support frame shown;

FIG. 2 is a first side elevation view thereof;

FIG. 3 is a second side elevation view thereof;

FIG. 4 is a front elevation view thereof;

FIG. 5 is a back elevation view thereof;

FIG. 6 is a top plan view thereof;

FIG. 7 is a bottom plan view thereof;

FIG. 8 is a perspective view of second embodiment of an earplug support frame, embodying our new design, a mirror image earplug support frame is evident from the earplug support frame shown;

FIG. 9 is a first side elevation view thereof;

FIG. 10 is a second side elevation view thereof;

FIG. 11 is a front elevation view thereof;

FIG. 12 is a back elevation view thereof;

FIG. 13 is a top plan view thereof; and,

FIG. 14 is a bottom plan view thereof.

The broken lines shown are included for the purpose of illustrating the unclaimed portions of the article and form no part of the claim.

1 Claim, 8 Drawing Sheets
